SHEET END STABILIZER AND METHOD OF USE

Charles P. Crampton, Hamilton, Ohio, assignor to The Hamilton Tool Company, Hamilton, Ohio, a corporation of Ohio

Filed Apr. 7, 1965, Ser. No. 446,302
20 Claims. (Cl. 271—69)

This invention relates to improvements in a collator and press delivery, and concerns the arranging of sheets severed from a continuously moving web of material such as paper, in single or multiple ply form.

An object of the invention is to provide improved means for severing sheets from a continuously moving web, and compiling the severed sheets in echelon arrangement with great precision and rapidity, to maintain reliable scheduled production unattended by frequent malfunctioning of the machinery.

Another object of the invention is to attain maximal reliability and efficiency in the delivery of sheets as stated, utilizing simple and inexpensive means which easily may be applied to machines in use, as well as to machines in the process of manufacture.

A further object is to provide means for the purposes stated, which demands practically no maintenance attention, and is characterized by extraordinary durability and longevity.

The foregoing and other objects are attained by the means described herein, and as disclosed in the accompanying drawings, in which:

FIG. 1 is a fragmentary top plan view of a delivery in which is embodied the means of the present invention.

FIG. 2 is a cross-sectional view taken on line 2—2 of FIG. 1.

FIG. 3 is a perspective view of a sheet guide which constitutes an element of the invention.

With reference to the accompanying drawings, the reference character W indicates a flexible web of paper or the like, which may be fed continuously from a source of supply such as a rotary reel, not shown. The web moves at high linear speed between a cut-off roll 6 and an anvil roll 8, which cooperate to transversely sever the advancing web at prescribed locations, to produce a continuous flow of sheets S1, S2 and S3. The severed sheets are to be deposited upon a rapidly moving conveyor 10, with the sheets overlapping one another in succession to produce an echelon arrangement. The overlapped sheets advance to the left in FIG. 2, and are eventually batched and deposited in or upon a suitable receiver, not shown.

The cut-off roll may carry one or more knives or cutters 12 to sever the web and thereby produce sheets of a predetermined length. Rolls 6 and 8 are power driven in opposite directions of rotation.

From the cut-off station, the severed sheets pass over a bridging element or plate 14 which directs the sheets in succession to the bite between gripper roll 16 and gripper wheel (1/4" wide) 18. The gripper roll and wheel are rotated in opposite directions at a surface speed exceeding the speed of web W, so as to tension sheet S1 and thereby ensure separation of said sheet from the web as cutter 12 penetrates the web. The greater speed imparted to sheet S1 serves also to propel the sheet over the top of sheet S2 with a partial overlap, to produce an echelon arrangement of the sheets.

From the disclosure at the left in FIG. 2, it is apparent that the leading edge 20 of sheet S2 overlaps the trailing edge 22 of sheet S3; in like manner, projection of sheet S1 by the gripper roll and wheel will cause the leading edge 24 of S1 to over-ride the trailing edge 26 of sheet S2, by an amount approximating the overlap of sheet S2 upon sheet S. As will be understood, the upper run of con-

2

veyor 10 is driven at a slower linear speed than the surface speed of gripper roll 16 and gripper wheel 18. The speed of the conveyor may be subject to regulation, so as to establish the amount of sheet overlap desired upon the conveyor.

The pair of rolls 6—8, and gripper roll 16 and gripper wheel 18, as well as the conveyor roll 28, may be driven by conventional means common in the art. Power driven also is the shaft 30 carrying the knock-down fingers 32, which perform to flatten down the trailing ends of successive sheets upon a stationary bridging element 34 just prior to projection of a succeeding sheet by the gripper roll. The bridging element 34 is mounted upon the machine frame 9, and spans the space between the lower gripper roll 16 and the support roll 28 of conveyor 10.

The knock-down device may be constituted of a series of spaced wires or light-weight thin bars, having ends 36 fixedly secured in spaced relation upon a mandrel 38 which rotates in clockwise direction with shaft 30. When shaft 30 is rotated to displace the finger 32 from the path of advancement of a sheet such as S1, said sheet may freely be projected by the gripper roll to overlie a portion of the preceding sheet, for example sheet S2. The timing of knock-down shaft 30 is such that fingers 32 will never be in a position to interfere with forward advancement of a sheet projected by the gripper roll.

In the past, operation of the delivery sometimes was interrupted by reason of failure of a gripper-projected sheet to properly over-ride a preceding sheet in sufficiently flattened condition; that is, the leading end of the projected sheet sometimes had a tendency to follow the periphery of gripper roll 16, and in so doing, tended to under-ride rather than over-ride, the trailing end 26 of a preceding sheet. This resulted in a jam at the knock-down mechanism, necessitating a halt in operation until the jam of sheets could be cleared.

One of the objects of the present invention is to obviate the above-mentioned difficulty and thereby avoid resultant expensive delays and annoyances.

It will be noted that the lower gripper roll 16 is provided along its length with a multiplicity of narrow radial grooves 40 spaced apart, the grooves being of substantial depth, and each groove having a base 42 defined by parallel side walls 44. The depth of each groove greatly exceeds the width thereof preferably, and all the grooves are of uniform depth.

The bases of the grooves provide tracks upon which may rest a series of sheet stabilizers 46 (see FIG. 3), which fit loosely between the side walls of the grooves so that the stabilizers may remain stationary while the roll 16 rapidly rotates. The side walls of the grooves support the stabilizers in upright position, or in planes normal to the axis of rotation of the roll.

The stabilizers 46 are identical one to another, and FIG. 3 discloses one such stabilizer in detail. It comprises a piece of sheet material of uniform thickness, shaped to provide a head 48 and an elongate integral tail 50. The upper and lower edges 52 and 54 defining the tail 50, may be straight edges convergent in the direction of the free end of the tail. The head 48 likewise may be defined by upper and lower straight edges 56 and 58, respectively, which are divergent in the direction of the outer end 60 of the head. The lower edges 54 and 58 meet at an obtuse angled juncture 62, which is free of contact with the base 42 of a groove when the stabilizer is seated therein.

As FIG. 2 clearly indicates, the lower straight edges of the head and the tail have point-contact with the track provided by the groove base, so that running friction between the stabilizer and the track is held to a practical minimum. To further minimize running friction, the sta-

bilizer may be formed of Teflon, Delrin, or a similar plastic substance which possesses self-lubricating, wear-resistant characteristics. In the example illustrated, the thickness of the stabilizer approximates one-sixteenth, which allows gripper wheel 18 (1/4 inch wide) to be placed directly over sheet stabilizer 46 if desired.

In order that the upper gripper wheel 18 may cooperate with the lower gripper roll in propelling or projecting a sheet such as S1 without interference by the stabilizer, the height dimension of the stabilizer tail may be less than the depth of groove 40, where the roll and wheel establish full contact with the sheet. The line of full contact, of course, is in a plane which includes the axis of roll 16.

At the head end of the stabilizer, the upper sheet-support edge 55 projects toward a knock-down finger 32, and is substantially tangent to the outer periphery of roll 16. Edge 56 generally will be disposed in a plane which is above, and substantially parallel to, the upper reach of conveyor 10.

It is desirable that the stabilizer head, and particularly the delivery end of its edge 56, be located over a portion of the bridging element 34, so that the leading end 24 of a sheet such as S1 may be firmly supported against downward sag until said leading end overtakes the trailing end of a preceding sheet, S2, traveling in the same direction. Thus, the leading end 24 of a sheet being projected by gripper roll 16 and gripper wheel 18, is precluded from underlapping the trailing end of the preceding sheet.

To ensure the stabilizer against displacement as the lower gripper roll 16 rotates, the head end of the stabilizer may be provided with a notch 64 to engage the forward edge 66 of bridging element or plate 34. If desired, the free end of the stabilizer tail 50 may for the same purpose be tucked beneath the free edge portion 63 of bridging element 14, as shown in FIG. 2. Either or both of these expedients may be employed to preclude rotation of the stabilizer with the lower gripper roll.

It should be understood that all of the sheet-supporting devices or stabilizers 46, will bear the above disclosed relationship to the gripper roll and wheel and to those elements of the machine which act upon sheets projected by the gripper roll and wheel in the direction of advancement of conveyor 10. The web W and the sheets severed therefrom, may be single-ply, multiple-ply, or laminate in character. In many instances the web may comprise several layers of paper between which may be interposed copy-paper layers carbonized or otherwise treated for the production of copies. Portions severed from such webs are collated by the machine in the same manner, and with the same effectiveness, as single sheets.

It is to be understood that various modifications and changes may be made in the structural details of the device, within the scope of the appended claims, without departing from the spirit of the invention.

What is claimed is:

1. Apparatus for stacking upon a receiving surface a series of flexible sheets fed in linear succession from a source of supply, said apparatus comprising: driven means including the periphery of a rotary gripper roll for projecting said sheets in succession, with corresponding ends of successive sheets in leading position; a rotary knock-down device adjacent to the driven means aforesaid, to engage only the trailing end portions of the sheets projected by said driven means and flatten said end portions upon the receiving surface; and a sheet end stabilizer intermediate the driven means and the knock-down device, for guiding the leading ends of successive projected sheets tangentially from the gripper roll periphery.

2. Apparatus according to claim 1, wherein the receiving surface comprises a moving conveyor traveling at a lesser surface speed than that of the gripper roll periphery, and wherein the stabilizer guides the leading ends of the sheets onto the conveyor in a plane which

is above and in substantial parallelism with the plane of the conveyor.

3. Apparatus for stacking upon a receiving surface a series of flexible sheets fed in linear succession from a source of supply, said apparatus comprising: driven means including a rotary gripper roll having a periphery for projecting said sheets in succession, with corresponding ends of successive sheets in leading position, said gripper roll having formed in its periphery a plurality of narrow radial grooves spaced apart, the grooves each having a base defined by parallel side walls, a sheet stabilizer upon and supported by the roll and loosely fitted in each groove between the side walls thereof, said stabilizers each having a head end and a tail adapted to be supported upon the base of a groove, an upper guide edge on each stabilizer extended substantially tangentially from the supporting gripper roll periphery toward the sheet receiving surface, for precluding the leading ends of the sheets from following the moving periphery of the gripper roll, and directing said ends toward the receiving surface in substantial parallelism with the latter; and means precluding rotation of the stabilizer with the gripper roll.

4. Apparatus according to claim 3, wherein the receiving surface comprises a moving conveyor traveling at a lesser surface speed than that of the gripper roll periphery, and wherein the stabilizer edge guides the leading ends of the sheets onto the conveyor in a plane which is spaced above the plane of the conveyor.

5. Apparatus for stacking upon a receiving surface a series of flexible sheets fed in linear succession from a source of supply, said apparatus comprising: driven means including a rotary gripper roll underlying the sheets and having a periphery for engaging and projecting said sheets in succession, with corresponding ends of successive sheets in leading position, said gripper roll having formed in its periphery a plurality of narrow radial grooves spaced apart, the grooves each having a base defined by a pair of spaced side walls, a stationary sheet stabilizer comprising a flat head loosely fitted in each groove between the side walls thereof and supported upon said base of the groove, an upper guide edge on each stabilizer head, with said guide edge extended substantially tangentially from the gripper roll periphery toward the sheet receiving surface, to preclude the leading ends of the projected sheets from following the moving periphery of the gripper roll.

6. Apparatus according to claim 5, wherein the receiving surface comprises a planar moving conveyor traveling at a lesser surface speed than that of the gripper roll periphery, and wherein the stabilizer guide edge directs the leading ends of the projected sheets onto the conveyor in a plane which is spaced above, and in substantial parallelism with, the plane of the conveyor.

7. Apparatus according to claim 6, wherein is included a knock-down device located between the stabilizer head and the conveyor, operative to depress the trailing end of a projected sheet in advance of projection of a succeeding sheet over the conveyor by action of the gripper roll.

8. Apparatus for stacking upon a receiving surface a series of flexible sheets fed in linear succession from a source of supply, said apparatus comprising: driven means including a rotary gripper roll having a periphery for engaging the undersides of and projecting said sheets in succession, with corresponding ends of successive sheets in leading position, and a stationary sheet stabilizer slidably mounted upon and supported by the gripper roll, and said stabilizer including means to preclude the leading ends of the roll-projected sheets from following the contour of the gripper roll periphery as said roll rotates.

9. Apparatus according to claim 8, wherein the means last mentioned includes a sheet-guiding surface directing the leading ends of the projected sheets in substantial parallelism with the plane of the receiving surface, said

sheet-guiding surface being substantially tangential to the periphery of the gripper roll.

10. Apparatus according to claim 9, wherein the receiving surface comprises a planar moving conveyor traveling at a lesser surface speed than that of the gripper roll periphery, to induce stacking of the sheets in echelon fashion upon the conveyor.

11. Apparatus for stacking upon a receiving surface a series of flexible sheets fed in linear succession from a source of supply, said apparatus comprising: driven means including a rotary gripper roll having a radially grooved periphery to contact and project said sheets in succession, with corresponding ends of successive sheets in leading position, the radial grooves of the gripper roll being spaced apart along the length of the roll, and each groove having a base defined by a pair of spaced side walls, a flat elongate sheet-stabilizer loosely fitted between the side walls of each groove, each stabilizer comprising a head and an integral tail supported within a groove, a straight bearing edge on the head, and a straight bearing edge on the tail, said bearing edges meeting at an obtuse angle intermediate the ends of the stabilizer, said edges being adapted to ride in point-contact abutment upon the base of a roll groove as the roll rotates relative to the stabilizer, a guide edge on the head disposed outside the limits of the groove, said guide edge being substantially tangential to the periphery of the gripper roll, and the stabilizer tail at the point of contact of the bearing edge of the tail upon the groove base, being of lesser height than the depth of the groove.

12. Apparatus according to claim 11, wherein at least one end of the stabilizer includes an abutment to contact a stationary part of the apparatus, for precluding rotation of the stabilizer with the gripper roll.

13. Apparatus according to claim 11, wherein the stabilizer is formed of a self-lubricating, wear-resistant resin material selected from the group consisting of acetyl and polytetrafluoroethylene resins.

14. A sheet-stabilizer for application to a gripper roll having a radial groove defined by a groove base and a pair of spaced side walls extending outwardly from said base to the periphery of the roll, said stabilizer comprising: a flat elongate body loosely receivable between the side walls of the groove, with point-contact abutment upon the base of the groove, and a sheet-guiding edge on the body disposed outside the limits of the groove, said guiding edge being substantially tangential to the periphery of the gripper roll, and an abutment on the stabilizer body for anchoring the body against rotation with the gripper roll.

15. A sheet-stabilizer according to claim 14, wherein the abutment aforesaid is exposed outside the limits of the groove of the gripper roll.

16. A sheet-stabilizer according to claim 14, wherein the stabilizer body is formed of a self-lubricating, wear-resistant resin material selected from the group consisting of acetyl and polytetrafluoroethylene resins.

17. Apparatus according to claim 1, wherein said sheets are projected freely in advance of being contacted by said knock-down device.

18. Apparatus for stacking upon a receiving surface a series of flexible sheets fed in linear succession from a source of supply, said apparatus comprising: means forming a receiving surface, driven means closely adjacent to said receiving surface including the periphery of a rotary gripper wheel for projecting said sheets in succession onto said surface with corresponding ends of successive sheets in leading position, the sheets being engaged on the under surface thereof by said roll, a rotary knock-down device between and closely adjacent to said driven means and said surface operative to engage only the trailing end portions of the sheets projected by the driven means and flatten said end portions on said receiving surface, sheet stabilizing means lying between the driven means and said knock-down device for supporting suc-

cessive sheets projected tangentially from the gripper roll periphery onto said surface, said stabilizing means embodying a plurality of elongate members extending transversely across the gripper roll and having top edges on and along which said successive sheets move, means maintaining said elongate members in stationary operative position relative to the gripper roll, said sheet receiving surface comprising an end portion of the top run of an endless conveyor moving in the same direction as the projected sheets, and said knock-down device comprising a rotary shaft over and extending across said end portion of said conveyor top run and a plurality of flexible fingers carried by said rotary shaft and turned thereby in a rotary path to move in the direction of movement of the projected sheets when knocking the sheets down toward the said receiving surface.

19. Apparatus according to claim 18, with a bridging member between said gripper roll and the said end portion of the said top run of said endless conveyor, said 20 bridging member having a top surface lying below the said top edges of said elongate members and substantially in the plane of said sheet receiving surface.

20. Apparatus for stacking upon a receiving surface a series of flexible sheets fed in linear succession from a source of supply, said apparatus comprising: a cut-off roll and a cooperating anvil roll between which a sheet of flexible material passes to be cut transversely to produce a flow of individual sheets moving in one direction, means forming a receiving surface comprising an 25 end portion of the top run of an endless conveyor moving in said one direction of flow of said sheets, driven means closely adjacent to said end portion of said conveyor including a gripper wheel and an underlying gripper roll between which wheel and roll said sheets are fed and from 30 which they are projected by said gripper roll in succession onto said receiving surface with corresponding ends of successive sheets in leading position, said gripper roll having a radially grooved periphery in contact with the periphery of said gripper wheel, the radial grooves of 35 the gripper roll each having a base defined by a pair of spaced side walls, flat elongate sheet-stabilizers each loosely fitted in one of said grooves transversely of and between said wheel and roll, each stabilizer comprising a head and an integral tail, said head and tail having bottom bearing edges intermediate the ends of the stabilizer, said bearing edges resting and riding upon the base of a 40 groove as the roll rotates relative to the stabilizer, a top guide edge on the head of each stabilizer outside the limits of the groove, said top guide edge being substantially tangential to the periphery of the gripper roll, the stabilizer tail at the point of contact of the bearing edge thereof upon the groove base being of lesser height than the depth of the groove, a bridging element extending 45 from adjacent the periphery of the anvil roll to and terminating over a terminal portion of said tail of each stabilizer, a bridging element between said gripper roll and said end portion of said endless conveyor, the last mentioned bridging element having a top surface lying below the said top guide edges of the stabilizers and substantially in the plane of said sheet receiving surface, 50 coupling means between said head of each stabilizer and said last mentioned bridging member, and a rotatable knock-down means overlying said end portion of said endless conveyor operative to engage the trailing end portions of the sheets projected by said driven means and flatten said end portions on said receiving surface.
